Fig. 5.

Fig. 6.

Fig. 7.

FIG. 1 is a side perspective view of a mounting bracket for bicycle showing our new design and its use with a bicycle, and a carrier, with the bicycle and carrier being shown in broken lines for illustrative purposes only,

FIG. 2 is a fragmentary front elevational view thereof with a portion of the upper tubular member broken away for convenience of illustration,

FIG. 3 is a fragmentary rear elevational view thereof with a portion of the upper tubular member broken away for convenience of illustration,

FIG. 4 is a rear perspective view thereof,

FIG. 5 is a top plan view thereof,

FIG. 6 is an exploded perspective view thereof with the upper tubular member omitted for convenience of illustration, it being understood that the broken line showing of the steering post is for illustrative purposes only,

FIG. 7 is a sectional view thereof taken along lines 7-7 of FIG. 1, it being understood that the broken line showing of the steering post is for illustrative purposes only.

We claim:

The ornamental design for a mounting bracket for bicycle, as shown and described.
